SHOE FOR OPENING A FURROW IN SEED PLANTING IMPLEMENTS

Donald E. Williams, Garden City, Kans., assignor to
Acra-Plant, Inc., Newton, Kans., a corporation of
Kansas

Filed Dec. 26, 1962, Ser. No. 72,954

Term of patent 14 years

(Cl. D35—2)

FIG. 1 is a side elevational view of a shoe for opening a furrow in seed planting implements, showing my new design.

FIG. 2 is a top plan view thereof;

FIG. 3 is a rear elevational view thereof;

FIG. 4 is a front elevational view thereof;

FIG. 5 is a transverse cross-sectional view taken on line 5—5 of FIG. 1;

FIG. 6 is a transverse cross-sectional view taken on line 6—6 of FIG. 1; and

FIG. 7 is a cross-sectional view taken on line 7—7 of FIG. 1.

I claim:

The ornamental design for a shoe for opening a furrow in seed planting implements, as shown.
